CHAIR BACK CONSTRUCTION

Stanley J. Gedris, Grand Rapids, Mich.

Application December 19, 1940, Serial No. 370,777

7 Claims. (Cl. 155—184)

The present invention relates to chair back construction and more particularly to the construction of the backs of chairs of the theater type. This application is a continuation in part of my co-pending application Serial No. 367,903 filed November 30, 1940.

The primary objects of this invention are to provide improved means for attaching an upholstery sheet to the back plate of a theater type chair back; to provide such improved attaching means which are convenient in assembly; to provide a chair back embodying said improved means for attaching the upholstery sheet to the back plate in which the back plate is so formed of sheet metal as to give an appearance of substantial thickness to said back plate and an appearance of massiveness to the chair without decreasing the amount of space behind the chair; and to provide a chair back construction which is rugged and sturdy, attractive in appearance, and economical in manufacture.

Illustrative embodiments of the invention are shown in the accompanying drawings, wherein:

Figure 1 is a rear perspective view of a theater chair mounted between two chair supporting standards and embodying my new construction;

Figure 2 is an enlarged fragmentary sectional view through the chair back taken on line 2—2 of Figure 1;

Figure 3 is a fragmentary perspective view of parts of the chair back prior to their assembly;

Figure 4 is a sectional view similar to Figure 2 but showing certain parts of the chair back in only partially assembled position;

Figure 5 is an enlarged fragmentary sectional view on line 5—5 of Figure 1;

Figure 6 is a sectional view similar to Figure 2 but showing a modified construction of chair back;

Figure 7 is a front perspective view of a chair back plate showing a further modified construction;

Figure 8 is an enlarged fragmentary sectional view thereof taken on line 8—8 of Figure 7 and showing in addition certain other parts of the chair back before their assembly with the back plate;

Figure 9 is an enlarged fragmentary sectional view of the parts shown in Figure 8, after their assembly; and

Figure 10 is a sectional view similar to Figure 2 but showing a further modified construction of chair back.

Referring now in detail to the drawings wherein like parts are designated by the same nu-

merals in the several views, the theater type chair shown in Figure 1 comprises a chair seat 10 and a chair back generally designated 11 mounted between and supported by a pair of horizontally spaced vertically disposed chair supporting standards 12. The seat 10 is preferably pivotally mounted on the standards 12 by suitable means such as the means shown in my co-pending application above identified.

The chair back 11 comprises a sheet metal back plate 13 having a continuous flange generally designated 14 extending around the top and sides of the back plate 13. This flange 14 comprises a portion 15 extending rearwardly from the main body of the back plate 13, a portion 16 extending outwardly from the portion 15, a portion 17 extending forwardly from the portion 16, and a vertical portion 18 extending inwardly from the portion 17. A continuous pocket 19 is thus formed extending around the top and sides of the back plate 13.

Padding 20 of suitable material such as cotton, hair or sponge rubber is disposed over the back plate 13, and an upholstery sheet 21 of fabric, leather or other suitable upholstery material is disposed over the padding 20. A rod or wire 22 is secured as by stitching 23 within a continuous hem 24 at the top and side margins of the upholstery sheet 21. A plurality of clips 25 are provided, each clip 25 having a portion 26 securely curled around the rod 22 and the hem 24 of the upholstery sheet 21, and a forwardly extending portion 27.

When the chair back is assembled, the front surface of the back plate 13 is covered with padding 20, and rod 22, hem 24 of the upholstery sheet 21 and the clips 25 secured thereto are pressed within the pocket 19 formed by the flange 14 on the back plate 13 as indicated in Figure 4, whereupon the forwardly extending portions 27 of the clips 25 spring outwardly, due to the pressure of the padding compressed in the operation, and engage behind the inwardly extending vertical portion 18 of the flange 14 on the back plate 13 to thus maintain these parts in secure assembly. An angle bracket 28 is secured to the front surface of the back plate 13 beneath the pocket 19 along the top of the back plate, and this bracket 28 supports the top portion of the padding 20 within the pocket 19 to insure compression of that padding during assembly of the chair back.

The back plate 13 is formed so as to provide means for readily mounting the chair back on and between the supporting standards 12. To

this end, the rearwardly extending portion 15 of the flange 14 is tapered to a considerably greater width at the sides of the back plate 13 than at the top thereof, as best seen in Figures 1 and 5. Fastening means such as the screws 29 are passed through apertures in the rearwardly extending portion 15 of the flange 14 and through the upholstery sheet 21, and are here shown threaded in the standards 12 to securely attach the chair back to the standards. Preferably and as here shown each standard 12 has a recess 30 therein, into which fits the adjacent flange 14 of the back plate 13.

In the modified form of the chair back shown in Figure 6, the construction is identical to that previously described except that the rearwardly extending portion 15¹ and the forwardly extending portion 17¹ of the flange 14¹ on the back plate 13¹ are of substantial forward-rearward length thus lending an appearance of substantial thickness to the back plate and of massiveness to the chair. This modified construction does not decrease the necessary amount of room behind the chair for the occupant of a chair in the rear thereof inasmuch as the rearwardly extended flange 14¹ is present only at the top and sides of the chair back.

Figures 7, 8 and 9 show a modified form of the invention in which an auxiliary plate 31 is substituted for the angle bracket 28 previously described. This auxiliary plate 31 has a central leaf 32 struck therefrom and secured as by spot welding 33 to the front surface of the back plate 13². The auxiliary plate 31 normally lies flush against the back plate 13². When this modified chair back is assembled, a quantity of padding 34 is pressed between the top margin of the auxiliary plate 31 and the back plate 13² as best seen in Figure 8. Padding 20² is next disposed over the auxiliary plate 31. The rod 22² and hem 26² of the upholstery sheet 21², and the clips 25², are then inserted into the pocket 19² in the back plate 13², and the compressed padding 34 exerts an upward pressure against the forwardly extending portions 27² of clips 25² to thus securely engage said portions behind the inwardly extending vertical portion 18² of the flange 14² on the back plate 13².

In the modified construction shown in Figure 10 a Z-shaped bracket 35 is secured to the front surface of the back plate 13³ beneath the pocket 19³ at the top of the back plate 13³. This bracket 35 has a vertically upwardly extending flange portion 36 disposed forwardly of the pocket 19³. In this form of the invention the clips 25³ have their forwardly extending portions 27³ adjacent the inner side of the upholstery sheet 21³, and when the chair back is assembled these portions 27³ engage behind the vertically disposed flange portion 36 of the bracket 35 to thus securely maintain the parts in assembly. A quantity of padding 37 is preferably compressed between each clip 25³ and the upholstery sheet 21³ to insure engagement of the clip portions 27³ behind the flange portion 36 of bracket 35.

It will thus be seen that a chair back has been provided which is simple and economical in construction, convenient in assembly and attractive in appearance and while but several specific embodiments of the invention have been herein shown and described, it will be understood that numerous details of these embodiments may be altered or omitted without departing from the spirit of the invention as the same is defined by the following claims:

I claim:

1. In a chair structure of the class described, a pair of horizontally spaced vertically disposed chair supporting standards, a chair back supported by said standards and comprising a back plate having a continuous forwardly opening pocket at the marginal top and sides thereof, a flange on said back plate having a vertical portion disposed forwardly of the pocket along the top of the back plate, padding over the back plate, an upholstery sheet covering the padding, a rod secured within a continuous hem at the top and side margins of the upholstery sheet and inserted within said pocket, and a plurality of clips each having a portion secured to said rod and hem and a forwardly extending portion adapted to engage behind the vertical portion of said flange on the back plate for maintaining the rod and the hem of the upholstery sheet within said pocket.

2. In a chair structure of the class described, a pair of horizontally spaced vertically disposed chair supporting standards, a chair back supported by said standards and comprising a back plate having a continuous flange at the top and sides thereof said flange extending rearwardly, then outwardly, then forwardly, and finally inwardly to form a pocket, padding over the back plate, an upholstery sheet covering the padding, a rod secured within a continuous hem at the top and side margins of the upholstery sheet and inserted within said pocket, and a plurality of clips each having a portion secured to said rod and hem and a forwardly extending portion adapted to engage behind the inwardly extending portion of the continuous flange on the back plate for maintaining the rod and the hem of the upholstery sheet within said pocket.

3. In a chair structure of the class described, a pair of horizontally spaced vertically disposed chair supporting standards, a chair back supported by said standards and comprising a back plate having a continuous flange at the top and sides thereof said flange extending rearwardly, then outwardly, then forwardly, and finally inwardly to form a pocket, padding over the back plate, an upholstery sheet covering the padding, a rod secured within a continuous hem at the top and side margins of the upholstery sheet and inserted within said pocket, and a plurality of clips each having a portion securely curled around said rod and the hem of the upholstery sheet and a forwardly extending portion adapted to engage behind the inwardly extending portion of the continuous flange on the back plate for maintaining the rod and the hem of the upholstery sheet within said pocket.

4. In a chair structure of the class described, a pair of horizontally spaced vertically disposed chair supporting standards, a chair back supported by said standards and comprising a back plate having a continuous flange at the top and sides thereof said flange extending rearwardly, then outwardly, then forwardly, and finally inwardly to form a pocket, padding over the back plate, an upholstery sheet covering the padding, a rod stitched within a continuous hem at the top and side margins of the upholstery sheet and inserted within said pocket, and a plurality of clips each having a portion secured to said rod and hem and a forwardly extending portion adapted to engage behind the inwardly extending portion of the continuous flange on the back plate for maintaining the rod and the hem of the upholstery sheet within said pocket.

5. In a chair structure of the class described, a pair of horizontally spaced vertically disposed chair supporting standards, a chair back supported by said standards and comprising a back plate having a continuous flange at the top and sides thereof said flange extending rearwardly, then outwardly, then forwardly, and finally inwardly to form a pocket, padding over the back plate, an upholstery sheet covering the padding, a rod secured within a continuous hem at the top and side margins of the upholstery sheet and inserted within said pocket, a plurality of clips each having a portion secured to said rod and hem and a forwardly extending portion adapted to engage behind the inwardly extending portion of the continuous flange on the back plate for maintaining the rod and the hem of the upholstery sheet within said pocket, and means secured to the back plate for supporting the upper portion of the padding adjacent said pocket.

6. In a chair structure of the class described, a pair of horizontally spaced vertically disposed chair supporting standards, a chair back supported by said standards and comprising a back plate having a continuous flange at the top and sides thereof said flange extending rearwardly, then outwardly, then forwardly, and finally inwardly to form a pocket, the rearwardly extending portion of said flange being relatively wider

at the sides of the back plate than at the top thereof but the outwardly, forwardly and inwardly extending portions of said flange being uniform throughout the length of the flange, 5 padding over the back plate, an upholstery sheet covering the padding, means for securing the top and side margins of the upholstery sheet within said pocket, and fastening means passing through the rearwardly extending portions of 10 said flange at the sides of the back plate and into the adjacent chair standards respectively for securing the chair back to the standards.

7. In a chair structure of the class described, a pair of horizontally spaced vertically disposed 15 chair supporting standards, a chair back supported by said standards and comprising a back plate having a continuous flange at the top and sides thereof said flange extending rearwardly, then outwardly, then forwardly and finally inwardly to form a pocket, the rearwardly and forwardly extending portions of said flange being of substantial forward-rearward length to lend an appearance of substantial thickness to the back plate, padding over the back plate, an upholstery sheet covering the padding, and means for 20 securing the top and side margins of the upholstery sheet within said pocket.

STANLEY J. GEDRIS.
